CLAIM

The ornamental design for a cigar and accessory holder, as shown and described.

DESCRIPTION

FIG. 1 is a perspective view of a cigar and accessory holder showing my new design; and,

FIG. 2 is a front elevational view thereof.

The opposite perspective view of the cover portion of the holder is a mirror image of FIG. 1. The even broken line showings within the shaded area denote stitching lines which are a part of my claimed design. The uneven broken line showings of the boundaries of the claim, the cigars and accessories and the remainder of a carrying case are for illustrative purposes only and form no part of the claimed design.
